UNITED STATES PATENT OFFICE.

MAX E. MOELLER, OF BROOKLYN, NEW YORK

HYDROMETER.

1,177,128.

Specification of Letters Patent. Patented Mar. 28, 1916.

Application filed May 28, 1915. Serial No. 30,480.

To all whom it may concern:

Be it known that I, MAX E. MOELLER, a citizen of the United States, and a resident of the borough of Brooklyn, in the county of Kings, State of New York, have invented certain new and useful Improvements in Hydrometers, of which the following is a specification.

The improvements relate to hydrometers, and more particularly to instruments of this character designed to be used in connection with a vessel provided with means for extracting a small amount of liquid from other vessels and testing its specific gravity. In such instruments the vessel is provided with a nozzle of some kind and a suction device, such as a compressible bulb, and the hydrometer is located inside the vessel, which is made of glass or other transparent material so that the graduation marks of the hydrometer may be read therethrough. A vessel of this character is necessarily small, and it is desirable that it be constructed so as to require as little liquid as possible to fill it to the desired extent and float the hydrometer. Considerable difficulty, however, has been found in instruments of this character on account of the fact that the hydrometer comes in contact with the walls of the vessel in which it is located, adheres slightly thereto and prevents a correct reading. The buoyancy of the hydrometer is of course necessarily feeble, and therefore a slight adhesion between it and the walls of the vessel will interfere seriously with that buoyancy. Efforts have been made to overcome this objection, but so far as I am aware it has not been cured to such an extent as to render the instrument reliable under all conditions of use. If the instrument is held carefully in a vertical position, and the inner surfaces of the vessel are kept dry the difficulty can be avoided in most instances. This, however, is not to be relied upon. In testing electric batteries, for instance, considerable carelessness is exhibited by those in charge of the work, and very often it is convenient or necessary to place the instrument at an angle to the vertical when extracting liquid for testing purposes, and in addition to this if the nozzle is not kept submerged while the liquid is being drawn into the vessel, air will be drawn in and will cause it to splash and moisten the said vessel from top to bottom. I have discovered that all these matters may be

provided for and the instrument made safe and dependable under all conditions, by the construction and arrangement hereinafter described and claimed.

To these ends the objects of the invention, among others, are to provide an extracting device and hydrometer so constructed and arranged as to give an accurate reading under various conditions and even if carelessly handled, and to provide a simple, compact and sufficiently capacious device which will be convenient to handle and meet all the other requirements.

The invention consists in the construction, combination and arrangement of parts hereinafter described and claimed and illustrated in the accompanying drawings.

In the said drawings, the figure is a vertical medial section of a vessel with liquid extracting means and hydrometer embodying the improvements.

The compressible bulb A has its neck passed over the open hollow neck of the vessel B and is held in a state of expansion thereon. To the opposite end of the said vessel a tube D of rubber or similar material is secured by being expanded and forced over the hollow nipple C, and in the lower or outer end of this tube a glass tube E is placed so as to extend a suitable distance therefrom and provide a nozzle which may be immersed in the solution to be tested for the purpose of withdrawing a part of the same, and through which the contents of the testing device are discharged.

The hydrometer proper F is of ordinary form, and consists of a weighted bulb G and a stem H with graduation marks thereon. It is normally located in the lower part of the vessel B, and a rubber or other cushion I is provided to prevent the bulb from breaking through contact with the bottom of the vessel. This hydrometer is of such shape and proportions that it will co-operate with the peculiar construction of the vessel as hereinafter described.

The vessel B consists of three sections or compartments J, K and L. The lower compartment L is slightly greater in diameter than the bulb of the hydrometer, and a little longer than the said bulb, so that the bulb may rise and fall freely therein when buoyed by the liquid, and will not pass out of the same before it has been raised to a sufficient extent for the operator to easily observe that it is free from the bottom and floating in

the liquid. The intermediate compartment K is somewhat greater in diameter than the compartment L and shorter, and the compartment J is of still greater diameter and approximately the same length. It will thus be observed that in effect there is provided a vessel flaring upwardly from its lower vertically walled compartment to provide for the increased distance subtended by the angle within which the lower portion of the compartment may vibrate. As the vibration of the hydrometer stem in the vessel is limited by the walls of the compartment L, with which the bulb comes in contact, and the extreme angle with respect to the vertical which this stem may assume will not bring it in contact with the walls of J or K, such contact is thereby insured against. The length of the compartment L is such that the bulb, and its appended stem will float before liquid of any density recordable by the hydrometer has risen to the intermediate chamber K, and the bulb will therefore be within this compartment or chamber L when the instrument floats and indicates the specific gravity. Contact between the bulb and the walls of the chamber L will also take place, when the level is at and above the level of liquid necessary to float the hydrometer, only in the liquid. This prevents any adhesion. This is provided for by the relative proportions of the parts and the weight of the hydrometer. If the bulb were permitted to come in contact with the walls above the liquid or if the stem were permitted to do so, a slight adhesion would take place, due to the presence of moisture at the point of contact and the air pressure surrounding it. This adhesion would be sufficient to render the instrument entirely unreliable and give incorrect readings, with all the undesirable consequences. Nor can this result be avoided, in an instrument where such contact is permitted, by care on the part of the operator, since the hydrometer when shaken so as to free it from contact with one wall will almost invariably fall against and adhere to the opposite wall. It will be seen therefore that the improved construction herein described, although involving relatively small modifications in detail of construction accomplishes a very important result, and in fact renders an unreliable instrument absolutely reliable and dependable under all conditions of use.

It will be understood that the compressible bulb A may be made of such size and capacity that when compressed and allowed to expand it will draw in a sufficient quantity of liquid to fill the vessel to the desired height, and also that other details of construction may be added and modifications of the details shown and described made without departing from the spirit and scope

of the invention. It will also be observed that if more liquid than is necessary is drawn into the vessel it will not rise materially above the compartment K owing to the greatly increased capacity of the compartment J, and that the bulb will thus be prevented from rising into the former compartment.

What I claim is:

1. In a device of the character described, the combination of a transparent vessel, a device for determining the specific gravity of liquid comprising a bulb and a stem located in said vessel, means for filling the said vessel with liquid to a point at which said device will float, the relative sizes of the part of the vessel in which the hydrometer bulb remains and of that part containing the hydrometer stem being such that in the extreme inclined position possible for the bulb of the floated hydrometer its stem cannot touch the walls of the vessel.

2. In a device of the character described, the combination of a liquid extractor, comprising a vessel into which the liquid is drawn and in which it is held, a hydrometer in said vessel consisting of a stem and a bulb contracted and weighted to float on the liquid in an upright position, said stem projecting upwardly from the bulb, and having graduations thereon, whereby the specific gravity of the liquid is determined by the level of the liquid with respect to the stem, the lower part of said vessel being contracted and receiving said bulb and limiting the lateral movement of the same to such an extent that the stem is held at all times out of contact with the walls of the vessel.

3. The combination of a vessel adapted to receive and contain liquid to be tested for specific gravity, and a hydrometer within said vessel, said vessel having a contracted lower part and the lower part of the hydrometer remaining in said contracted part while testing the specific gravity of a liquid, the relative size of the hydrometer with respect to the contracted lower portion being such that the level of a liquid heavier than water at the floating point of the hydrometer is above all points of possible contact between the hydrometer and the walls of the said vessel.

4. The combination of a floating hydrometer and a vessel adapted to contain liquid to be tested in which said hydrometer is located, the relative sizes of the vessel and the hydrometer being such that when at its floating point and extreme inclined position possible for the said floated hydrometer it cannot touch the walls of the vessel above the liquid level therein.

5. The combination of a floating hydrometer and a vessel adapted to contain liquid in which it is located, said vessel having a

relatively large upper chamber, a contracted lower portion and an intermediate portion larger than the contracted lower portion and smaller than the upper, the three parts forming a continuous receptacle, and the hydrometer having its bulb in the lower portion and its stem extending through the intermediate into the upper portion the size of the lower portion in relation to the other portions being such that the hydrometer, when at its floating point and extreme inclined position, cannot touch the walls of the upper portions with its stem.

6. The combination of a floating hydrometer and a vessel adapted to contain liquid to be tested, said vessel having a contracted lower portion and an enlarged upper por-

tion and said hydrometer having an enlarged bulb in said contracted portion and a relatively narrow stem in said enlarged portion, the relative size of the bulb and the contracted lower portion being such that oscillatory movement of the bulb while in said contracted lower portion is limited to such an extent as to prevent the stem or contracted portion from coming in contact with the walls of the enlarged portion within which it is located.

Witness my hand this 17th day of May, 1915, at the city of New York, N. Y.

MAX E. MOELLER.
